Specification for Design.

Patented Jan. 4, 1921.

Application filed February 21, 1920. Serial No. 360,418. Term of patent 7 years.

To all whom it may concern:

Be it known that I, WILLIAM S. STOTHOFF, residing at Easton, in the county of Northampton and State of Pennsylvania, have invented a new, original, and ornamental Design for Tractor-Wheels, of which the following is a specification, reference being had to the accompanying drawing, forming part hereof.

Figure 1 is a face view of a tractor wheel, showing my new design; and

Fig. 2 is an edge view thereof, partly in section.

I claim:—

The ornamental design for a tractor wheel, as shown.

WILLIAM S. STOTHOFF.
